UNITED STATES PATENT OFFICE.

JOHN DALBY, OF PAWTUCKET, RHODE ISLAND, ASSIGNOR, BY MESNE ASSIGNMENTS,
TO RHODE ISLAND LACE WORKS, A CORPORATION OF RHODE ISLAND.

WARP-WINDING DEVICE.

1,330,583.

Specification of Letters Patent. Patented Feb. 10, 1920.

Application filed May 22, 1918. Serial No. 236,016.

To all whom it may concern:

Be it known that I, JOHN DALBY, a subject of the King of Great Britain, residing at Pawtucket, in the county of Providence and State of Rhode Island, have invented 5 certain new and useful Improvements in Warp-Winding Devices, of which the following is a specification.

My invention relates to devices for delivering and winding threads or strands upon 10 warp rolls.

In lace machines the rolls for carrying the warp strands are much longer than those for looms, and the devices employed for 15 winding loom beams are inadequate mechanically and economically when attempted to be employed in winding lace warp rolls. It has heretofore been attempted to wind the strands upon lace warp rolls by arranging in series end to end a number of winding 20 mills with a creel or jack in front of each mill, an operator for each mill manually reciprocated a jack longitudinally thereof, while each mill wound from its corresponding 25 jack a plurality of bands. After this operation the lace warp roll was mounted for rotation in a separate machine, and drew and wound from the mills the constituent strands of bands. This procedure required 30 numerous operators, much time, and several operations, and presented an irregularity in the density of the winding on the warp roll, resulting in an unsatisfactory fabric.

The essential objects of my invention are 35 to overcome the disadvantages cited; to wind a warp beam of unusual length in a single operation; to insure a hard, compact, and uniform density of winding upon the beam; to deliver to the beam a maximum number 40 of strands by means occupying a minimum of space; to accurately guide the strands therefrom without confusion; to uniformly tension the strands; and to facilitate the threading of the strands through the thread 45 plates. Further objects of invention will appear from an examination of the drawings and the following description.

To the above ends essentially my invention consists in such parts and combinations 50 of parts as fall within the scope of the appended claim.

In the accompanying drawings which are 55 a part of this specification, and in which is shown merely a preferred form of embodiment of my invention,

Figure 1 is a plan view of my complete apparatus, the spools being omitted from several of the jacks,

Fig. 2, a side elevation of the same 60 omitting some of the spools and jacks,

Figs. 3 and 4, rear and end elevations respectively of the portable brasses or reed plates.

Fig. 5 a front elevation of a relatively stationary brass or reed plate, and 65

Fig. 6, a transverse section of the tension roll and adjacent rolls.

Like reference characters indicate like parts throughout the views.

In its present and preferred embodiment 70 my apparatus includes a plurality of creels or jacks 15 radially arranged side by side, the number of jacks being determined by the length of the warp beam intended to be wound. Each jack comprises a single vertical frame consisting of end posts 16, standards or bases 17 and cross bars 18 having converging faces 19, carrying spindles 20. Adjacent the spindles are guides 21. Upon one of the posts 16 are pivotally mounted 80 series of horizontally disposed laterally projecting arms 28, arranged in pairs in horizontal alignment with each other, and with the apex of each cross rod 18. In the top of each arm is fixed a series of wire guide 85 eyes 34. In the bottom of the arm is another series of similar eyes 37 staggered relatively to the eyes 34. The number of eyes in the top row should exceed by one the number of eyes in the bottom row.

The spindles or posts 20 loosely receive the spools 40 whose threads 41 pass through the eyes 34 and 37.

The preferred form of mechanism for 95 drawing and winding the strands delivered from the jacks consists of any frame best adapted for carrying the operating parts, such as end uprights 43 having spaced upwardly directed arms 44, midway between which are grooves or open bearings 45 adapted to receive the shaft 47 of a tension roll 48. Integral with the upper portions of the uprights are rearwardly directed brackets 49 one of which is provided with a slot 50 to receive the shaft 51 of the warp roll 52. Resting in slots 53 in the tops of the arms 44 are the shafts 55 of idler rolls 56. As shown in Fig. 6 the roll 48 has a fabric covering 58, and the rolls 56 have a similar covering 59. The driving means includes a 100 105 110

main shaft 61 journaled in the uprights carrying driving pulleys 62, a wheel 63, and momentum wheel 64. A second shaft 65 in the uprights carries a gear 66 and wheel 67 5 driven by a belt 68 on the wheel 63. The gear 66 meshes with a gear 70 fast on a shaft 71 mounted in a bearing 73 on the bracket and having a coupling 74 detachably engaging the warp roll shaft 51. By the 10 described or other convenient mechanism the warp roll is rotated.

For temporarily elevating the idler warp roll 58 from its seat the following mechanism is employed. The ends of the shaft 47 15 are loose in the ends of arms 75 fixed to shaft 76 journaled in sleeves 77 on a bracket 78 on the front of the uprights. Fast to the shaft is an arm 79 pivoted to one end of a connecting rod 81 whose other end is pivoted to the upper end of a lever 83 mounted intermediate its length upon a pin 84 in a standard 85 whose base 86 is fixed to the floor. Upon the base is pivoted a latch 87 20 pressed by a spring 88 and located in the path of a pedal 90 provided with a bevel 91 to assist engagement with the latch when the lever is depressed.

Fast to the uprights outside the rolls 56 in the front and rear of the frame are the 25 longitudinal bars 93 and 94 respectively, formed of angle iron. Removably attached by screws 97 to the face of the upright portion of the bar 93 are a series of brasses, thread plates, or reeds 98 arranged edge 30 to edge in each plate, as shown in Fig. 5. Each plate has four horizontal rows of 35 five perforations 99, and below said rows are parallel rows of four perforations 100 in staggered or inclined relation to the 40 perforations of the first mentioned rows. The number of perforations in each row corresponds with the numbers of guide eyelets 34 and 37 respectively, on a single jack; and the number of sets of rows, namely four, 45 correspond with four of the arms 28 upon the jack. A greater number of perforations than used may be employed. The number of plates 98 are sufficient to receive through their perforations the strands 41 of all the 50 spools on the jack which pass over the rolls 56 and under roll 48. In the present instance the strand from the four lower right hand rows of spools of the first jack pass through the end plate 98; the strands from 55 the upper four right hand rows, through the next adjacent plate 98; those from the lower four left hand rows, through the third plate; and those of the four upper left hand rows, through fourth plate.

60 The strands after passing over the back

roll 56 traverse a series of thread plates 102 arranged end to end on the bar and engage the warp beam. These plates have rows of perforations 103 and 104 corresponding in number and arrangement with 65 the perforations 99 and 100 respectively. These plates are preferably arranged several deep as shown in Fig. 4. When so arranged a convenient method of attachment consists of dowel pins 106 in the bar which 70 pass loosely through openings 107 in the plates. In an opening 108 in the bar is the shank 109 of a clamp having a finger 110 engaging the rearmost plate. A nut 111 on the threaded opposite end 112 of the shank 75 operates the clamp. The reason for the multiple arrangement of the plates 102 is that when the filled warp beam is removed from the machine, the plates 104 in the rearmost row are also removed with the 80 beam and maintain the several strand ends separate.

The operation of the machine is as follows: The warp beam 52 is placed in the frame and engaged by the coupling 73 to the 85 shaft 71 which is rotated by the driving shaft 61 through the described driving connections. The strands 41 having been threaded as described and engaged at their ends to the beam, are now drawn from the jacks. 90 The passage of the strands over the rollers 56 and under roller 48 imparts the necessary tension to the series.

In threading the strands through the rear plates 102 after threading the front plates 95 98 requires ample room. This is secured by elevating the roll 58 temporarily above the horizontal plane of the rolls 56 and plates. The elevation is effected by depressing the 100 pedal 90 which is thereupon engaged by the latch 87, and the beam remains elevated during the threading operation.

I claim:

In an apparatus of the character described, the combination with the jacks, the warp 105 frame, the warp beam, and means for driving the same, of tension rolls on the frame between the beam and jacks for supporting strands from the jacks, an idler roll resting in the frame intermediate and below the 110 first rolls, a rock shaft journaled in the frame adjacent the idler roll, arms on the shaft engaging the ends of the idler roll, a third arm fast to the rod at an angle to the first arms, and means for vibrating the third 115 arm.

In testimony whereof I have affixed my signature.

JOHN DALBY.
